US00D731741S

(12) **United States Design Patent**
Brown et al.

(10) **Patent No.:** US D731,741 S
(45) **Date of Patent:** ** Jun. 16, 2015

(54) **FILLED CRACKER PRODUCT**

(71) Applicant: **Frito-Lay North America, Inc.**, Plano, TX (US)

(72) Inventors: **Martha Jo Meadows Brown**, Grapevine, TX (US); **Susan Patricia Licker**, McKinney, TX (US); **Jose Michel Nader**, Dallas, TX (US); **Shalaka Narwankar**, Plano, TX (US); **Thomas Stingelin**, Plano, TX (US)

(73) Assignee: **FRITO-LAY NORTH AMERICA, INC.**, Plano, TX (US)

(**) Term: **14 Years**

(21) Appl. No.: **29/471,577**

(22) Filed: **Nov. 1, 2013**

(51) LOC (10) Cl. **01-01**

(52) U.S. Cl. **D1/128**
USPC ....

(57) **CLAIM**

The ornamental design for a filled cracker product, as shown and described.

DESCRIPTION

FIG. 1 is a perspective view of the filled cracker product according to a first embodiment;

FIG. 2 is a front view of the filled cracker product according to a first embodiment;

FIG. 3 is a back view of the filled cracker product according to a first embodiment;

FIG. 4 is a left side view of the filled cracker product according to a first embodiment;

FIG. 5 is a right side view of the filled cracker product according to a first embodiment;

FIG. 6 is a top view of the filled cracker product according to a first embodiment;

FIG. 7 is a bottom view of the filled cracker product according to a first embodiment;

FIG. 8 is a perspective view of the filled cracker product according to a second embodiment;

FIG. 9 is a front view of the filled cracker product according to a second embodiment;

FIG. 10 is a back view of the filled cracker product according to a second embodiment;

FIG. 11 is a left side view of the filled cracker product according to a second embodiment;

FIG. 12 is a right side view of the filled cracker product according to a second embodiment;

FIG. 13 is a top view of the filled cracker product according to a second embodiment; and,

FIG. 14 is a bottom view of the filled cracker product according to a second embodiment.
